UNITED STATES PATENT OFFICE.

JAMES F. McDONNELL, OF CLEVELAND, OHIO, ASSIGNOR TO EMIL SCHWARZ, OF CHICAGO, ILLINOIS.

BRUSH.

1,317,303.

Specification of Letters Patent. Patented Sept. 30, 1919.

Application filed July 24, 1916, Serial No. 110,986. Renewed March 17, 1919. Serial No. 283,261.

To all whom it may concern:

Be it known that I, JAMES F. McDONNELL, citizen of the United States, residing at Cleveland, in the county of Cuyahoga and 5 State of Ohio, have invented a certain new and useful Improvement in Brushes, of which the following is a full, clear, concise, and exact description, reference being had to the accompanying drawings, forming a 10 part of this specification.

My invention relates to brushes and is of particular service in the formation of a brush employed for washing the interior of bottles or other containers. The invention 15 has for its general object the simplified and improved formation of a brush from a body of resilient or cushioning material such as rubber.

In practising my invention I provide a 20 plurality of cleaning fingers in a body of rubber, the tips of some of these fingers being in union to form of fingers thus united a spring structure joining other fingers and 25 yieldingly limiting the extent to which the other fingers may be spread apart while the brush is in action and operating to retract the same when the operation of the brush ceases or the speed of such operation is reduced. Thus the extent to which some of the 30 brush fingers may be spread is yieldingly limited by the fingers whose tips are united and varies according to the speed of the spindle which carries the brush.

I will explain my invention more fully by 35 reference to the accompanying drawing showing the preferred embodiment of my invention and in which Figure 1 is a perspective view showing the brush of my invention in action; Fig. 2 shows the brush in elevation 40 and in an inactive condition; Fig. 3 shows the brush in elevation while in action, a part of the brush structure being shown in section; and Fig. 4 is a perspective view of a water conveying tube that desirably enters 45 into the construction.

Like parts are indicated by similar characters of reference throughout the different figures.

The stock 1 is attached to the upper end 50 of a spindle forming part of a bottle washing machine, the lower end of the stock being threaded for this purpose. The stock is hollow for the passage of water and is preferably crimped at its upper end as indicated

at 2 for the purpose of engaging the intermediate portion of the base 3 of the brush structure whereby the stock and brush structure are held in firm engagement. Union between the brush structure and the stock is further promoted by means of the water 55 conveying tube 4 that passes through the base portion 3, this tube being outwardly flared at its ends to form wings or flanges 5 between which the base portion of the brush structure is received and which wings 60 co-operate with the annular fastening portion 2 to prevent movement of the base 3 longitudinally of the stock. The water that is 65 conveyed through the stock desirably issues therefrom through the bore of the tube 4 so 70 that said tube serves a double purpose.

The brush structure is desirably of symmetrical formation having a pair of central fingers 6 and 7 that spring from the base 3 and which have their tips in union, the tip 75 portions of the fingers 6 and 7 being desirably integral. The base or inner portions of the fingers 6 and 7 are desirably respectively integral with the base or inner portions of the fingers 8 and 9 between which 80 fingers 6 and 7 are disposed, the fingers 6 and 7 preferably separating from the fingers 8 and 9 remote from the base 3, intermediate portions of the additional fingers 8 and thus being respectively connected with 85 fingers 6 and 7. The fingers 8 and 9 are themselves desirably bifurcated at their upper ends to form sub-fingers 8¹, 9¹, the tips of these sub-fingers being desirably tapered as illustrated most clearly in Fig. 1. The 90 base portion 3 and the washing fingers are desirably integrally formed out of one piece of rubber whereby no supplemental mechanical means are required for joining the fingers with their common base 3, though I 95 do not wish to be limited to this arrangement. The united tip portions of the middle fingers 6 and 7 form a comparatively thick substantial cleaning body that may have effective scraping action upon the surfaces being cleaned while the tapered tips 100 of the sub-fingers 8¹, 9¹ will effectively enter the curves and corners to be cleaned. The overlapping sub-fingers upon each main finger (8 or 9) reinforce each other in presenting a substantial cleaning body to the surfaces being cleaned but are highly flexible by reason of their separation so that 105

they are readily adapted to varying surfaces.

The fingers 6 and 7 by being merged or united at their tip ends constitute a spring structure for yieldingly limiting the extent to which the fingers 8 and 9 may be spread apart and substantially maintaining the fingers 8 and 9 in the same plane with the fingers 6 and 7. Thus each finger may perform its cleaning function without material interference from the other fingers. When the brush is not in action the spring structure 6 and 7 serves to draw in the fingers to have approximately the relative arrangement illustrated in Fig. 2 in which the brush structure may readily be inserted within and withdrawn from the bottles and the guiding sleeve that is employed to direct the passage of the brush structure into and out of the bottles.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

30. 1. A brush structure having two fingers formed of resilient cushioning material, the tip portions of these fingers being united; and an additional finger adjacent each of the aforesaid fingers, the latter being located 35 between the additional fingers and connected with intermediate portions thereof, the first two fingers together constituting a

spring for drawing the remaining fingers toward each other.

2. A brush structure having two fingers 40 formed of resilient cushioning material, the tip portions of these fingers being united and an additional finger whose intermediate portion is united with one of the aforesaid fingers that together constitute a spring 45 for drawing the remaining finger inwardly.

3. A brush structure having two fingers formed of resilient cushioning material, the tip portions of these fingers being united; and an additional finger adjacent each of the aforesaid fingers, the latter being located between the additional fingers and connected with intermediate portions thereof, the first two fingers together constituting a 50 spring for drawing the remaining fingers 55 toward each other, all of said fingers being integrally formed of the same piece of material.

4. A brush structure having two fingers formed of resilient cushioning material, the tip portions of these fingers being united; and an additional finger whose intermediate portion is united with one of the aforesaid fingers that together constitute a spring for drawing the remaining finger inwardly, all 65 of said fingers being integrally formed of the same piece of material.

In witness whereof I hereunto subscribe my name this twenty first day of July, A. D. 1916.

JAMES F. McDONNELL.
